UNITED STATES PATENT OFFICE.

MARVIN E. MCGILL, OF MADISON, GEORGIA.

PENCIL.

Application filed March 22, 1928. Serial No. 263 837.

This invention relates to pencils and has for a particular object thereof the provision of a pencil which may be readily sharpened without the assistance of a knife or other cutting implement.

A further and more specific object of the invention is to provide a pencil, the lead of which is provided with a casing formed of paraffine or some other suitable wax-like substance, which will not soften from the heat of the hand and which, at the same time, may be readily removed from the lead by the application of heat thereto or scraped from the lead by the use of a thumb nail or a blunt instrument.

These and other objects I attain by the construction shown in the accompanying drawing, wherein for the purpose of illustration is shown a preferred embodiment of my invention and wherein:

Figure 1 is a side elevation of a pencil constructed in accordance with my invention;

Figure 2 is an enlarged longitudinal sectional view therethrough;

Figure 3 is a transverse sectional view therethrough.

Referring now more particularly to the drawings, the numeral 10 generally designates a lead of the type ordinarily employed in pencils which, in accordance with my invention, is surrounded by a cast casing 11 consisting of either a pure paraffine or paraffine mixed with wax and other substances to produce a composition which will not melt at body temperatures and which, at the same time, may be readily melted by the heat of a match applied thereto. About this casing, I provide a paper cover 12, the edges of which are joined to one another. This entire tube is joined to the casing 11 in the process of casting the same and serves to reinforce the casing and render the same rigid under slightly higher temperatures to which it might be subjected while in storage. This pencil may have applied to one end thereof

an eraser 13, which is connected to the pencil in the ordinary manner.

A pencil of this character may be sharpened by the use of a blunt instrument or may be sharpened by simply lighting a match and applying the flame to the end of the pencil to melt away the casing and burn away the cover.

Since the construction hereinbefore set forth is capable of a certain range of change and modification without materially departing from the spirit of the invention, I do not limit myself to such specific structure except as hereinafter claimed.

I claim:

1. A pencil comprising a lead and a surrounding casing of a substance maintaining its rigidity under body temperatures but melting readily upon the application of flame thereto.

2. A pencil comprising a lead and a surrounding casing of a substance maintaining its rigidity under body temperatures but melting readily upon the application of flame thereto, and a cover for said casing which is readily sectionally removable and reinforces said casing to stiffen the same and render the same rigid under temperatures which would otherwise permit the casing to flex and deform.

3. A pencil comprising a lead and a surrounding casing of a substance maintaining its rigidity under body temperatures but melting readily upon the application of flame thereto, and a reinforcing cover for said casing of readily combustible material.

4. A pencil comprising a lead and a surrounding casing of a substance maintaining its rigidity under body temperatures but melting readily upon the application of flame thereto, and a paper cover for said casing.

In testimony whereof I hereunto affix my signature.

MARVIN E. MCGILL.
